UNITED STATES PATENT OFFICE.

EDWARD PAQUETTE, OF WORCESTER, MASSACHUSETTS.

DESIGN FOR A BRICK.

SPECIFICATION forming part of Design No. 30,707, dated May 2, 1899.

Application filed April 7, 1899. Serial No. 712,178. Term of patent 14 years.

To all whom it may concern:

Be it known that I, EDWARD PAQUETTE, a citizen of the United States, residing at Worcester, in the county of Worcester and 5 State of Massachusetts, have invented and produced a new and original Design for a Brick, of which the following is a specification, reference being had to the accompanying drawings, forming a part thereof.

10 Figure 1 is an end perspective view of a brick, showing my design; and Fig. 2 is a top or bottom view of the same.

As shown in the drawings, my brick A is of 15 rectangular form and has parallel top and bottom surfaces B and parallel sides or edges C and parallel end portions D at the corners corresponding to an ordinary brick.

Intermediate the end corners, at one end of 20 the brick, is a wedge-shaped recess or depression a, having the inclined sides or edges b connected at their inner ends by the straight side or edge c to form a blunt angle. The line c is parallel with the end lines of the brick. On the opposite end of the brick, intermedi-

25 ate the end corners, is a wedge-shaped projection or extension d, having the inclined sides or edges e e connected at their outer ends by the straight side or edge f, as shown. The line f is parallel with the end lines of the brick. The size and shape of the projection or extension d at one end of the brick correspond 30 with the size and shape of the recess or depression a at the other end of the brick.

The leading feature of my design is the wedge-shaped recess or depression in one end 35 of the brick with the flat or blunt point and the correspondingly-shaped projection or extension on the other end of the brick, the shape and appearance of the rest of the brick corresponding with the shape and appearance 40 of an ordinary brick.

What I claim is—

The design for a brick, substantially as herein shown and described.

EDWARD PAQUETTE.
